UNITED STATES PATENT OFFICE.

JOHN PURDY, OF BROOKLYN, NEW YORK, ASSIGNOR TO THE MONARCH TYPEWRITER COMPANY, OF SYRACUSE, NEW YORK, A CORPORATION OF NEW YORK.

TYPE-WRITING MACHINE.

1,052,012.

Specification of Letters Patent.

Patented Feb. 4, 1913.

Application filed April 20, 1909. Serial No. 491,035.

To all whom it may concern:

Be it known that I, JOHN PURDY, citizen of the United States, and resident of the borough of Brooklyn, in the county of 5 Kings and State of New York, have invented certain new and useful Improvements in Type-Writing Machines, of which the following is a specification.

My invention relates to typewriting machines and more particularly to gages for the side edge of the paper.

One object of my invention is to provide simple and efficient means for effectively gaging the widthwise position of the paper 15 with reference to the platen.

A further object of my invention is to provide simple and efficient means for readily effecting an adjustment of the gage throughout, or substantially throughout, the 20 length of the platen.

A still further object of my invention is to render the gage readily detachable from the machine when desired.

To the above and other ends which will 25 hereinafter appear, my invention consists in the features of construction, arrangement of parts and combinations of devices to be hereinafter described and particularly pointed out in the appended claims.

In the accompanying drawings wherein 30 reference characters indicate corresponding parts in the various views, Figure 1 is a detail fragmentary plan view with parts broken away of a carriage of a Monarch machine embodying my invention. Fig. 2 is a transverse sectional view of the same. Fig. 3 is an enlarged detail transverse sectional view taken through the supporting bar for the gages at one of the 35 points of connection between the supporting bar and paper table. Fig. 4 is an enlarged detail transverse sectional view taken through one of the supporting devices for the gages and through the supporting bar 40 on which it is adjustably mounted.

I have shown in accompanying drawings only so much of the carriage of a Monarch machine as is necessary to illustrate my invention.

The carriage of a Monarch machine comprises a rear cross or slide bar 1 and forwardly projecting end bars 2. A platen shaft 3 extends through bearing openings in 45 the end bars 2 of the carriage and supports a rotative cylindrical platen 4. Finger

wheels 5 are provided at the ends of the platen shaft for rotating the platen. The usual combined platen and carriage scale 6 is mounted on supports (not shown) to travel with the carriage. A paper table 7 60 is provided with depending bifurcated brackets 8 which straddle the stems of headed screws 9 which are supported in tapped openings in lugs 10 that project forwardly from the slide bar 1 of the carriage. The 65 paper table is thus supported in place on the carriage. The paper table is apertured near the upper edge thereof to receive sockets or pockets 11 riveted at 12 to the paper table. These pockets are each adapted to receive a 70 pin or lug 13 riveted to and projecting from a supporting or rack bar 14 which extends throughout or substantially throughout the length of the paper table and platen and longitudinally of the paper table. The supporting bar is held on the front face of the paper table near the top edge thereof and close to the paper table as indicated in Figs. 1 and 2. The supporting bar 14 is provided with indices 15 which correspond to the indices on the combined platen and carriage scale and are situated, with reference to the length of the carriage, in the same positions as the indices on the carriage scale so that the index numeral "20" for instance on the 85 carriage or platen scale is in the same vertical plane as the corresponding numeral on the supporting bar 14. One edge of the supporting bar has interdental spaces 16; adjacent spaces being situated a letter space 90 distance apart. A locking part 17 is mounted at one end of a spindle 18 received in a slide or supporting device 19 and provided with a finger piece or head 20. A chamber 21 is formed in the supporting device 19 to 95 receive a coiled spring 22 which surrounds the spindle 18 and bears at one end against an end wall of the chamber and at the other end against the hub of the finger piece 20. Pressure of the spring 22 is thus exerted to move, 100 the locking head into one of the tooth spaces 16 to secure the device 19 in the position to which it is adjusted along the supporting bar 14. There are two of these devices 19, one situated ordinarily near the left-hand end of the supporting bar and the other near the right-hand end portion thereof. The left-hand device 19 has at its right-hand face a side edge paper gage 23 that is curved 105 forwardly and downwardly as indicated in 110

Fig. 2 to conform generally to the curvature of the paper table so that the gage may be supported close to the table. The contact face of the gage is in a plane at substantially 5 right angles to the length of the table and to the axis of the platen so as to present a contact face for coöperation with a side edge of the sheet. The right-hand side edge gage 24 is likewise supported on the inner face of its 10 companion supporting device 19. By this construction each of the side edge gages may be adjusted throughout or substantially throughout the length of the paper table and the platen or to any letter-space position 15 throughout the length of the platen in order to coöperate with sheets of any width at any point lengthwise of the platen.

As the sheets are introduced into the machine they are placed over the supporting bar 14 between the gages 23 and 24, the side edges of the paper being brought into contact with and squared against the side edge gages (or either one of them) and the paper is thus accurately directed to the platen at 20 any position in the length thereof determined by the setting of the gages. The indices on the supporting bar 14 corresponding to those on the carriage or platen scale enable the gages to be readily set to the desired positions without experiment.

While I have described the use of two paper gages 23 and 24, it should be understood that in some instances the employment of a single gage is sufficient.

35 If desired the supporting bar with the gages thereon may at any time be readily removed by withdrawing the pins 13 from the sockets 11 in which they are received.

What I claim as new and desire to secure 40 by Letters Patent, is:—

1. In a typewriting machine, the combination of a cylindrical platen, a paper table for supporting the paper as it is introduced into the machine, a bar supported on the 45 front face of the paper table contiguous thereto and extending longitudinally thereof, and a side edge gage carried by and arranged in front of said bar to gage paper passed in front of the bar, said gage being 50 slidably adjustable to different positions along said bar.

2. In a typewriting machine, the combination of a cylindrical platen, a paper table for supporting the paper as it is introduced 55 into the machine, a supporting bar supported on the front face of the paper table and extending longitudinally thereof, a carriage scale, indices on said supporting bar spaced to correspond to the spacing on the 60 carriage scale, and a side edge gage carried by and arranged in front of the bar and slidably adjustable to any letter space position along said supporting bar.

3. In a typewriting machine, the combination of a cylindrical platen, a paper table

for supporting the paper as it is introduced into the machine, a rack bar mounted on the front face of the paper table near the top edge thereof and extending throughout or substantially throughout the length of the 70 table, a carriage scale, indices on said rack bar corresponding to the carriage scale, a side edge gage, and a supporting device for said gage, said supporting device being slidably adjustable along said rack throughout the length thereof and having relatively movable means for engaging the teeth of said rack to hold the gage in its adjusted position.

4. In a typewriting machine, the combination of a cylindrical platen, a paper table for supporting the paper as it is introduced into the machine, a rack bar detachably mounted on the front face of the paper table near the top edge thereof and extending 85 throughout or substantially throughout the length of the table, a carriage scale, indices on said rack corresponding to the carriage scale, a side edge gage extending along the front face of the paper table in a plane at 90 right angles to the length of the table, the gage conforming generally to the shape of the table, and a supporting device for said gage detachable with the rack bar, said supporting device being slidably adjustable 95 along said rack throughout the length thereof and to any position corresponding to a like position indicated on the carriage scale and having relatively movable means for engaging the teeth of said rack to hold the 100 gage in its adjusted position.

5. In a typewriting machine, the combination of a cylindrical platen, a paper table for supporting the paper as it is introduced into the machine, sockets in the paper table, a supporting bar having engaging devices that are received in said sockets in the paper table to detachably support the supporting bar on the paper table, and a side edge gage 105 adjustable along said supporting bar.

6. In a typewriting machine, the combination of a cylindrical platen, a paper table for supporting the paper as it is introduced into the machine, sockets in the paper table, a supporting bar having engaging devices 115 that are received in said sockets in the paper table to detachably support the supporting bar on the paper table, said bar extending longitudinally throughout or substantially throughout the length of the 120 paper table, and a side edge gage adjustable along said supporting bar throughout or substantially throughout the length of said bar.

7. In a typewriting machine, the combination of a cylindrical platen, a paper table for supporting the paper as it is introduced into the machine, sockets in the paper table near the upper end or edge thereof, a rack bar having pins that are received in said 125

sockets for detachably supporting the rack bar on the paper table, said rack bar extending longitudinally of the table substantially throughout the length thereof, a carriage scale, indices on the rack bar corresponding to the carriage scale, a side edge gage extending along the paper table in a plane at right angles to the length of the paper table and conforming generally to the 10 shape of the table, a supporting device for said gage, said supporting device being adjustable along said rack bar substantially throughout the length thereof and having

spring pressed means for engaging the teeth of said rack bar to hold the gage in the 15 position to which it is adjusted along said bar.

Signed at the borough of Manhattan, city of New York, in the county of New York, and State of New York, this 19th day of 20 April A. D. 1909.

JOHN PURDY.
